UNITED STATES PATENT OFFICE

136,451

DESIGN FOR A TOY CANDY CONTAINER

Turney H. Stough, Jeannette, Pa.

Application August 11, 1943, Serial No. 110,884

Term of patent 14 years

To all whom it may concern:

Be it known that I, Turney H. Stough, a citizen of the United States, residing at Jeannette, in the county of Westmoreland and State of Pennsylvania, have invented a new, original, and ornamental Design for a Toy Candy Container, of which the following is a specification, reference being had to the accompanying drawing, forming part thereof.

In the drawing:

I claim:

The ornamental design for a toy candy container, as shown.

TURNEY H. STOUGH.
